CLAIM

The ornamental design for a sanitizing case, as shown and described.

DESCRIPTION

FIG. 1 is a perspective view of a sanitizing case showing our new design in an expanded configuration;

FIG. 2 is a front side view of the sanitizing case of FIG. 1;

FIG. 3 is a rear side view of the sanitizing case of FIG. 1;

FIG. 4 is a left side view of the sanitizing case of FIG. 1;

FIG. 5 is a right side view of the sanitizing case of FIG. 1;

FIG. 6 is a top end view of the sanitizing case of FIG. 1;

FIG. 7 is a bottom end view of the sanitizing case of FIG. 1;

FIG. 8 is a perspective view of a sanitizing case showing our new design in a collapsed configuration;

FIG. 9 is a front side view of the sanitizing case of FIG. 8;

FIG. 10 is a rear side view of the sanitizing case of FIG. 8;

FIG. 11 is a left side view of the sanitizing case of FIG. 8;

FIG. 12 is a right side view of the sanitizing case of FIG. 8;

FIG. 13 is a top end view of the sanitizing case of FIG. 8;

and,

FIG. 14 is a bottom end view of the sanitizing case of FIG. 8.

The broken lines depict portions of the sanitizing case that form no part of the claimed design.

1 Claim, 6 Drawing Sheets
